UNITED STATES PATENT OFFICE.

JOHN C. HOOD, OF WILKINSBURG, PENNSYLVANIA.

SLIDING WINDOW.

SPECIFICATION forming part of Letters Patent No. 583,375, dated May 25, 1897.

Application filed November 6, 1896. Serial No. 611,239. (No model.)

To all whom it may concern:

Be it known that I, JOHN C. HOOD, a citizen of the United States, residing at Wilkinsburg, in the county of Allegheny and State of Pennsylvania, have invented new and useful Improvements in Windows; and I do hereby declare the following to be a full, clear, and exact description of the same.

The invention relates to that class or description of windows which are provided with vertically-movable sashes; and its object is to provide an improved construction of the same by which the sash is securely held against rattling, while at the same time it will not stick or bind, so that it can be readily raised and lowered.

The invention consists in the novel construction and combination of parts hereinafter fully described and claimed.

20 In the accompanying drawings, Figure 1 is a longitudinal sectional view of a window-sash and a portion of a window-frame with my improvements applied thereto. Fig. 2 is a horizontal section on the line X Y, Fig. 1. Fig. 3 is an elevation showing a portion of the side of a vehicle provided with my improvements and also showing means for inflating the pneumatic tubes.

25 In the said drawings the reference-letter A designates the glass of a sliding-window sash, and B the frame thereof. The vertical side rails of this frame are formed with concave grooves, in which are seated concavo-convex plates E, securely fixed to said rails.

30 The letter F designates the side rails of a window-frame, formed in the inner side with semicylindrical vertical grooves, in which is seated a flexible pneumatic tube D, provided at the lower end with a nipple G, extending 35 through an opening in the lower rail of the window-frame. These nipples are to be provided with valves, (not shown,) and the tubes can be inflated by an ordinary air-pump.

35 The letter C designates a vertical concavo-convex strip, crescent-shaped in cross-section, interposed between each pneumatic tube and the plate E of the window-sash. The lower ends of these strips fit in recesses H in the lower rail of the window-frame, whereby their 40 movement is limited, while their upper ends are free.

A window provided with my improvements will possess superior advantages, as the sash will not rattle, and will not stick or bind, yet a perfectly tight joint will be formed, so as 55 to exclude dust and water.

In Fig. 3 I have shown my improvements applied to the windows of a railway-car which is provided with air-brakes. (Not shown.) The nipples G in this instance are connected 60 by means of branch pipes O with a horizontal pipe M, connected in turn by a pipe N with the train-pipe. (Not shown.) By this means the tubes can be inflated by the air-brake compressors, suitable valves of course being provided at proper points.

While I have shown the plates E and strips C as being concavo-convex, they may be made rectangular or flat, if desired.

Having thus fully described my invention, 70 what I claim is—

1. The combination with a window-frame the side rails of which are formed with semicylindrical grooves in their inner sides and the lower rail formed with a recess near each 75 end and the pneumatic tubes located in said grooves having nipples at the lower ends passing through openings in said lower rail, of the window-sash, the vertical plates secured to the side rails thereof, and the strips interposed between said tubes and plates with their lower ends resting in the recesses in the lower rail of the window-frame, substantially as described.

2. The combination with a window-frame 85 having semicylindrical grooves in the inner sides of the side rails and the lower rail formed with a recess near each end, and the pneumatic tubes located in said grooves provided with nipples passing through openings in said 90 lower rails, of the window-sash having a concave groove in the side rails, the concavo-convex plates seated in said grooves, the vertical strips crescent-shaped in cross-section interposed between said tubes and plates with their lower ends resting in the recesses in the lower rail of the window-frame, substantially as described.

3. In a railway-car provided with an air-brake system, the combination with the window-frame, having semicylindrical grooves in the inner sides of the side rails and the lower

rail having a recess near each end, the pneumatic tubes having nipples at the lower ends projecting through openings in said lower rail, the window-sash, the plates secured to the side rails thereof, and the strips interposed between said plates and tubes, of the branch pipes connected with said nipples, the horizontal pipe connected therewith and the pipe

connected with said horizontal pipe and adapted to be connected with the train-pipe 10 of the car, substantially as described.

JOHN C. HOOD.
